UNITED STATES PATENT OFFICE.

WILLIAM BURGYES, OF CHELSEA, MASSACHUSETTS.

IMPROVEMENT IN SWEAT-BANDS FOR HATS.

Specification forming part of Letters Patent No. 35,011, dated April 22, 1862.

To all whom it may concern:

Be it known that I, WILLIAM BURGYES, a citizen of the United States of America, and a resident of Chelsea, in the county of Suffolk and State of Massachusetts, have invented a new and useful Improvement in Hats; and I do hereby declare the same to be fully described in the following specification, and represented in the accompanying drawings, of which—

Figure 1 is a vertical and Fig. 2 a horizontal section of a hat provided with my invention. Fig. 3 is a view of its leather head-lining as separated from the hat-body.

My invention has reference to what is termed a "self-adjusting head-lining" for a hat; and it consists in a peculiar arrangement and combination of an inelastic and flexible band, with the leather flexible or elastic head-lining, and an air-space between the lining and the body of the hat.

In the drawings, *a* exhibits a hat-body, while *b* is its self-adjusting head-lining, which is generally flexible and made of leather, and is sewed at its upper edge to the hat-body. There is a space, *d*, between the lining and the hat-body, and for the purpose of enabling the lining to accommodate itself to the form or shape of the head on which the hat may be worn, the air-space being also to prevent grease or perspiration from passing from the lining into the hat-body. The head-lining, when so made and applied to a hat, is very apt while being worn, or afterward, to become

stretched, and particularly when more or less wet with perspiration from the head of a person, in which case the hat becomes either too loose on the head or is worn with discomfort. In order to obviate this difficulty, I combine with the said lining *b* an inelastic but flexible band, *e*, which I extend around its outer surface and cement thereto by means of an india-rubber or water-proof cement. The band should be arranged as shown in the drawings, and may be made of linen cloth covered with india-rubber to render it water-proof and capable of adhering to the leather lining by what is usually termed "india-rubber cement"—that is, caoutchouc dissolved in an essential oil, such as oil of turpentine.

By the employment of the inelastic flexible band in connection with the lining made and arranged in the hat, and with respect to an air-space, as specified, the lining will not only be caused to retain its proper shape, but the hat can be worn with much more comfort to a person than when the lining is unprovided with the band.

I therefore claim as my invention—

The above-described arrangement and combination of the inelastic and flexible band *e*, with the head-lining *b*, and the air-space *d*, arranged between the hat-body and head-lining, and for the purpose as set forth.

WM. BURGYES.
